UNITED STATES PATENT OFFICE

THEODORE K. LADD, OF COMANCHE, TEXAS, ASSIGNOR OF ONE-HALF TO JACK R. STEPHENS, OF COMANCHE, TEXAS

AUTOMATIC GATE

Application filed March 11, 1929. Serial No. 346,030.

This invention is an automatic gate for highways. The object is to provide a relatively simple, practical and efficient gateway and gate for locating across highways, the

same being adapted for automatic operation and opening through the weight of a vehicle such as an automobile. More specifically, the object is to provide a double gate weighted so as to automatically close when opened, and having runways pivotally connected therewith in such a manner that the weight of an automobile when driven upon the runways will serve to open the gates for the passage of the car.

15 In the drawings

Figure 1 is a side elevation of the preferred embodiment of my invention;

Figure 2 is a transverse vertical section on the line 2—2 of Figure 1.

20 In erecting my invention upon a highway 1, I provide a pit 2 transversely in the highway and mount pivot blocks 3 at either side of the roadway at one side of the pit. Angular gate supporting frames 4 are then piv-

25 oted at 5 to the vertical face of the blocks 3 so as to swing freely over the pit 2, the said frames having their lower ends 6 pendant into the said pit. Weights 7 are hung by cables 8 to the extremities of the end portions 6, and serve to keep the frames 4 in a normal upright position. Gates 9 are rigidly mounted in the frames 4 and, of course, open or close as the frames swing outwardly or inwardly, pivoting upon the points 5. A set

30 of runways 10 are positioned at each side of the gateway, their adjacent ends being loosely connected with the frames 4 at either side thereof by heavy pins 11 set rigidly through the frames and having their ends play loosely

40 in slots 12 of the plates 13 secured to the ends of the runways 10. These runways are extended out in opposite directions in parallel relation at either side of the roadway and their outer extremities are provided with

45 downwardly hooked anchor blocks 14 adapted to freely play in recesses 15 formed in the road bed. Guard blocks 16 are rigidly set at the outer sides of these ends of the said runways. A central subgate 17 is suspended

50 loosely by links 18 from the ends of one set

of the runways 10, below the gates 9, and this subgate is adapted to play vertically into and out of the pit 2 in the operation of the apparatus.

In operation, the weights 7 normally hold 55 the gates 9 in closed relation, and the subgate 17 raised. As a car moves onto the runways 10 at either side of the gates, the weight of the car depresses the frames 4, which pivoting upon the points 5 swing outwardly and 60 open the gates 9, the outer ends of which pass down into the pit 2, while their inner ends stand in an upright position, thus leaving a clear passage-way through between them. At the same time, the subgate 17 drops down- 65 ward into the pit and out of the way.

While I have herein described a certain specific manner and method of constructing and assembling the elements of my invention, it is understood that I may vary from the 70 same in minor details, not departing from the spirit of my invention, so as best to construct a practical device for the purpose intended, as defined in the appended claim.

I claim:

75 In a device of the kind described, in combination with a roadway having a transverse pit formed therein, a pair of gates pivotally mounted over the pit and adapted to open and close vertically thereover by passing 80 their outer ends into the pit, and runways at either side of the gates and having their ends loosely connected therewith at points outside the pivotal points of the gates, and a subgate loosely connected with the ends of a 85 set of the runways at one side of the gates and adapted to pass into and out of the said pit in the opening and closing of the gates.

In testimony whereof I affix my signature.

THEODORE K. LADD. 90
